LIGHT-METAL BARRACK

Heinrich Rauchholz, Berlin, Germany; vested in
the Alien Property CustodianApplication June 10, 1939, Serial No. 278,533
In Germany June 11, 1938

4 Claims. (Cl. 189—1)

My invention relates to light-metal barracks which are intended to be used instead of tents for military and other purposes, and especially of hospital tents.

It is an object of my invention to provide a light-metal barrack which is superior to tents because it can be erected and taken down more rapidly, is packed and transported more easily, possesses greater facilities for convenient equipment, and is more resistant to atmospheric influences while at the same time the structure is comparatively light.

To this end, I provide, in a light-metal barrack, a frame comprising a purlin member shaped as a ridge roof, a sole bar, and two end posts, all of light metal, in combination with means for detachably connecting the members of the frame.

The term "light metal" includes light metal proper, normally aluminium, and light-metal alloys.

A barrack according to my invention comprises at least two frames of the kind described. The parts of the frames are carried to the place where the barrack is to be built, the frames are assembled on the ground, erected and connected by top and bottom rails which are also of light metal, and are detachably connected to the end posts of the frames.

In the accompanying drawing,

Figs. 1, 2, and 3 are diagrammatic illustrations showing, respectively, the barrack in central longitudinal section, in end elevation, as viewed in the direction of the arrow X in Fig. 1, and in plan view.

Fig. 4 is a section on the line 4—4 in Fig. 1, drawn to a larger scale.

Fig. 5 is a section on the line 5—5 in Fig. 3, also drawn to a larger scale.

Fig. 6 is an elevation, showing part of the side frame illustrated in section in Fig. 5, and viewed from the left in that figure.

Referring to the drawing, the barrack is equipped with a side frame 48_l at the left, and a side frame 48_r at the right, as viewed in the direction of the arrow X, Fig. 1. The two side frames have plain cant rails 8'. Figs. 5 and 6 illustrate the bay between the intermediate posts 1a and 1b of the left side frame 48_l, and the panel 23 in the bay, with its solid lower portion, its row of windows 29, and row of ventilators 30, and the cant rail 8' at the top. The panel is held by a pair of cotters 25 in the webs of the posts 1a and 1b, and more cotters—not shown—at other points which give the panel a firm hold in its bay.

The upper ends of the posts are secured to the cant rail 8' by bolts 62 inserted in holes 49 in the posts and the cant rail, and the lower ends of the posts are anchored in the base frame of the barrack, as will now be described. The rectangular base frame comprises a pair of longitudinal bars 46_l and 46_r, and a pair of transverse bars 45. The bars are all of inverted channel section, and their flanges are supported by blocks 22, as shown in Fig. 5 for the bar 46_l. The end posts and intermediate posts of the side frames 48 are equipped with hooks 47 at their lower ends, as shown for the intermediate post 1b in Fig. 5 with which they engage in holes in the inverted channel bars 46. By these means, the posts are anchored firmly and, at the same time, are readily detachable.

The central frame is different from the two side frames 48_l and 48_r in that it merely comprises a beam girder 42 which is preferably made of lattice work, and triangular in cross-section, and a pair of V struts 43 and 44 at either end. Their upper ends are detachably secured to the sides of the beam girder 42 by the means described, and their lower ends are anchored in the end bars 45 in a manner similar to the anchoring of the posts in the side frames in the longitudinal bars 46.

The central frame is so designed that when it, and the side frames 48, have been assembled on the ground and erected, the upper edge of the ridge beam 42 is at a higher level than the upper edges of the cant rails 8' in the side frames. Roofing, and preferably roofing plates, are placed on the tops of the three frames, and held at the ridge beam 42 by hooks 55 engaging in holes in their base plates 39. Means such as hooks and eyes, not shown, hold the roofing on the cant rails 8' of the side frames 48.

Obviously, the ridge beam 42 and the struts 43, 44 must be made so strong that the central frame will bear the weight of the roofing without being supported at intermediate points.

Floor beams 57 extend across the floor of the barrack, and hooks 58, Fig. 5, at the ends of the beams are inserted in holes in the webs of the channel longitudinal bars 46 of the base frame. Floor plates 56 are placed on the beams 57 and the outer ends of the floor plates serve as abutments for positioning the side frames 48.

To facilitate the storing, loading and shipping of the barracks, certain members of inconvenient length may be divided and the parts connected by hinges, as shown for the longitudinal and transverse members 46 and 45 of the base frame

at 60 and 60', respectively, and for the ridge beam 42 at 61.

The barrack described is light and rapidly and easily erected.

By way of example, a barrack whose base frame 45, 46 is 10 metres long and 6 metres wide, and which is 2 metres high inside, weighs only 2 tons, as compared with a similar barrack of wood and steel structure which weighs 12 tons. My novel barrack can be erected and taken down in 10 two hours.

I claim:

1. A building having vertical side and end walls, a ridge beam, supporting struts diverging from the ridge beam and located in the end walls only, whereby to leave the interior free, the struts extending from the foundation of the building to the ridge beam, and a roof supported by the beam and the side and end walls.

2. A construction as defined in claim 1, where-

in the side walls each comprise a cant-rail and two end posts, and wherein the ridge beam and struts comprise a central frame with its parts detachably connected.

3. A construction as defined in claim 1, wherein the side walls each comprise a cant-rail and two end posts, and wherein the ridge beam and struts comprise a central frame with its parts detachably connected, the ridge beam being of triangular cross-section and the struts being provided in pairs at each end of the ridge beam.

4. A construction as defined in claim 1, wherein the side walls each comprise a cant-rail and two end posts, and wherein the ridge beam and struts comprise a central frame with its parts detachably connected, the ridge beam being of skeleton form with means carried by such ridge beam to removably secure the roof thereto.

HEINRICH RAUCHHOLZ.
